UNITED STATES PATENT OFFICE.

CHARLES H. MILLER, OF BUFFALO, NEW YORK, ASSIGNOR, BY DIRECT AND MESNE ASSIGNMENTS, TO EDWARD S. WARREN, OF SAME PLACE.

CURTAIN-ROLLER.

SPECIFICATION forming part of Letters Patent No. 293,187, dated February 5, 1884.

Application filed March 12, 1877. Renewed March 31, 1879.

To all whom it may concern:

Be it known that I, CHARLES H. MILLER, of the city of Buffalo, in the county of Erie and State of New York, have invented certain new and useful Improvements in Curtain-Rollers, which improvements are fully set forth in the following specification, reference being had to the accompanying drawings.

My invention relates to that class of curtain-rollers which are provided with a bore or cavity in which is arranged a spiral spring for automatically raising the curtain. These curtain-rollers are provided with a round bar or rod arranged axially within the bore or cavity, so as to form a core for the spring. Previous to my invention this round bar or rod was formed separate from the curtain-roller, and secured at its outer end to a flattened shank held in one of the brackets, while the inner end 15 turned in a bearing-block arranged at the inner end of the bore. This construction is objectionable, for the reason that wooden curtain-rollers are frequently harder on one side than on the other, so that in boring the roller the 20 auger will have a tendency to run toward the soft side of the roller, whereby the bore is apt to be out of center, and frequently so much so as to cause the roller to split. Furthermore, the wooden center bar turning in the bearing-block at the inner end of the bore of the roller 25 is apt to bind therein, so as to interfere with the free movement of the curtain-roller.

The object of my invention is to overcome these difficulties; and its nature will be fully understood from the following description.

In the accompanying drawings, Figure 1 is a sectional elevation of my improved curtain-roller. Fig. 2 is a cross-section in line $\times \times$, Fig. 1.

Like letters of reference designate like parts in each of the figures.

A represents the wooden curtain-roller, provided with a bore, B, in which is arranged the spiral spring c.

D represents the round bar or rod, arranged axially within the bore B, and secured with its inner end to the roller A, so as to turn therewith.

E is a metallic bearing arranged near the outer end of the bore B, so as to receive the end of the bar D.

e is the flattened shank, formed with the bearing E, and held in a suitable bracket, f, so as to prevent the turning of the shank. The spiral spring c is secured with its outer end to the bearing E and with its inner end to the curtain-roller, as shown at c'.

The bar D is made in one piece with the curtain-roller A, the bore B and bar D being formed at a single operation by means of a hollow auger cutting an annular recess. The outer diameter of the auger is equal to the size of the bore, while the central opening of the auger corresponds with the thickness of the bar D. The latter forms a guide for the auger as the boring progresses, thereby preventing the auger from working toward one side of the roller and insuring perfect work being turned out in all cases. The bar D being formed in one piece with or secured to the roller A, the bearing-blocks formerly employed at the inner end of the bore are entirely dispensed with, and the binding of the bar thus prevented. As the bore B and bar D are formed at the same operation, all waste from the auger working out of center is avoided, and my improved curtain-roller produced at considerably less expense than the rollers heretofore in use.

Having thus described my invention, what I claim as new, and desire to secure by Letters Patent, is—

1. As a new article of manufacture, a wooden curtain-roller provided with the bore B, and having the axial bar D, made in one piece with the roller, substantially as and for the purpose hereinbefore set forth.

2. The combination, with the hollow roller A, of the bar D, formed therewith, so as to rotate with the roller, stationary bearing E e, in which the outer end of the bar D rotates, and spiral spring c, secured with its ends, respectively, to the roller A and bearing E, substantially as and for the purpose hereinbefore set forth.

CHARLES H. MILLER.
